[57] CLAIM

The ornamental design for an automotive trim panel clip removing tool, as shown and described.

DESCRIPTION

FIG. 1 is a front, top and side perspective view of an automotive trim panel clip removing tool showing my new design;

FIG. 2 is a front elevational view;

FIG. 3 is a side elevational view, the opposite side being a mirror image thereof;

FIG. 4 is a top plan view thereof;

FIG. 5 is a bottom plan view;

FIG. 6 is a rear elevational view; and,

FIG. 7 is a side elevational view showing the tool in an open position.

The automotive trim panel clip removing tool has been shown broken away in the middle in FIGS. 1-3, 6 and 7 to indicate indeterminate length.
